UNITED STATES PATENT OFFICE.

WILLIAM ALEXANDER MARTIN, OF COMMERCIAL CROSS, PRINCE EDWARD ISLAND,
CANADA.

ADJUSTABLE WRENCH.

1,423,723.

Specification of Letters Patent. Patented July 25, 1922.

Application filed December 10, 1921. Serial No. 521,416.

To all whom it may concern:

Be it known that I, WILLIAM ALEXANDER MARTIN, a subject of the King of Great Britain, and resident of Commercial Cross, 5 in Kings County, in the Province of Prince Edward Island, Dominion of Canada, have invented certain new and useful Improvements in Adjustable Wrenches, of which the following is a specification.

10 This invention relates to improvements in adjustable wrenches, and has for its objects to provide a wrench, in which the gripping space between the two jaws is designed to be easily and rapidly adjusted, to provide 15 a means to make this adjustment rapid and positive, to provide a wrench that can be easily operated with one hand, to provide a wrench formed with a movable jaw provided with a pawl designed to engage a series of 20 serrations formed on the shank of the wrench.

Further objects are to provide a means whereby the jaws will be tightened together on the handle being operated, to provide a 25 handle pivotally mounted to the shank of the wrench and to the serrated member slidably mounted thereon in order to tighten the jaws on the operation of the wrench.

Other objects are to provide an adjustable 30 wrench that is simple in construction, not liable to go out of repair, and generally to adapt the several parts to better perform the functions required of them.

With the above and other objects in view, 35 the invention consists essentially of the improved construction, hereinafter described in detail in the accompanying specification and drawings.

In the drawings;

40 Figure 1 is a side elevation of the improved wrench.

Figure 2 is a side view of the same, partly in section and partly in elevation.

Figure 3 is a perspective view of the pawl 45 member.

Figure 4 is a perspective view of the adjustable jaw.

Figure 5 is a side elevation of an alternative form of wrench.

50 Figure 6 is a side view of the same, partly in section and partly in elevation.

Figure 7 is a perspective view of the pawl member.

Figure 8 is a perspective view of the 55 adjustable jaw and extending arm.

Like characters of reference indicate corresponding parts in all the figures.

In the drawings; A represents the improved wrench comprising a shank 10 at the end of which a stationary jaw 11 is formed integral. The shank 10 is formed with a depressed portion providing a shoulder 12, which is formed with a recess 13. Slidably mounted on the depressed portion of the shank 10 is serrated member 14 formed at 60 one end with a pin 15 designed to engage the recess 13. A handle 16 is provided, which is pivotally connected to the end of the shank 10 opposite to that provided with a jaw 11, and is also pivotally connected to 65 each lug 17 formed at one end of the serrated member 14. It will be obvious that by means of this connection when the handle 16 is moved inwardly the fulcrum 18 on the shank will act as a pivot and the handle 70 being pivotally connected to the lug 17 as at 19, the serrated member 14 will be forced to slide on the depressed portion of the shank 10, and the member 14 moving on the same, the pin 15 will be forced to extend within 75 the recess 13 provided in the shoulder 12.

Slidably mounted on the shank 10 is a movable jaw 20 formed with a serrated working face 21 and provided with a slotted arm or link 22, which engages the shank 10. 80

The jaw 20 is formed with a rearwardly extending arm 23 formed with a pair of shoulders 24, which are apertured in alignment as shown at 25 in order to pivotally engage a pin 26 on which is mounted a pawl member 27, which is formed with a slotted arm or link 28 designed to engage the shank 10 and the serrated member 14. 85

The pawl member 27 is formed on one side of its fulcrum with a lip 29, and on the opposite side of its fulcrum with a pointed wedge 30, which is designed to engage the serrations formed on the serrated member 14. 90

A resilient member preferably a leaf spring 31 is fastened to the upper face of the arm 23, and the outer end of the spring 31 engages the underface of the lip 29 provided on the pawl 27. The working face of the stationary jaw 11 may be concave if desired, and provided with serrations 32. 100

When in operation, the works are engaged by the jaw 11, and the pawl 27 being forced obliquely upwards the movable jaw 20 is slid on the shank 10 of the wrench, and brought to bearing engagement with the 105 110

works. The pawl 27 is then released and the leaf spring 31 forcing the lip 29 upwardly, will force the wedge point 30 of the pawl 27 into engagement with the serrations 36 formed on the serrated member 14, the handle 16 being then forced inwardly in order to operate the wrench the fulcrum 18 acting as a pivot point. The pivoted end 19 of the handle 16 will force the lug 17 of the serrated member 14 inwardly, and the same moving towards the works will also move the pawl member 27, which is in engagement therewith through its wedge point 30 engaging the serrations and will therefore tighten the grip of the jaws 11 and 20 by lessening the space between the same.

Referring now to Figures 5 to 8 inclusive of the drawings, the shank 33 is formed integral with a handle 34 and the outer end of the shank 33 is also provided with a supporting jaw 35 formed integral therewith.

The shank 33 is provided intermediate of its length with serrations 36 and slidably mounted on the shank 33 is a movable jaw 37 formed with a slotted arm or link 38 engaging the shank 33.

The movable jaw 37 is formed with an arm 39 extending rearwardly of the jaw, and formed at its outer end with a pair of shoulders 40, which are bored in alignment as shown at 41. The bores 41 carry a pin 42 on which is pivotally mounted a pawl member 43 provided with a slotted arm or link 44 engaging the shank 33.

The pawl member 43 which is similar to that pawl member 27 previously described, is provided with a lip 45 on one side of its fulcrum, and a wedge point 46 on the opposite side thereof.

Fastened to the underface of the arm 39 is a resilient member 47 which is preferably a leaf spring, and the end of the leaf spring 47, which is offset as at 48 engages the outer face of the lip 45 and is designed to force the pawl member downwardly, thus causing the wedge point 46 to engage the serrations 36 provided on the shank 33.

It is obvious that the operation of this alternative form of wrench is the same as that of the preferred form previously described with the exception that no means are provided to tighten the jaws together, while operating the wrench.

The movable jaw 37 is moved along the

shank 33 by obviously raising the pawl member 43 in order to cause the wedge point 46 to disengage from the serrations 36 and be thus free to move along the shank.

As many changes could be made in the above construction, and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. An adjustable wrench comprising a shank, formed with a shoulder provided with a recess, a serrated member slidably mounted in the shank, and formed with a pin engaging the recess, a handle pivotally attached to one end of the shank, and to the serrated member, a jaw formed integral with the opposite end of the shank, an adjustable jaw slidably mounted on the shank, an arm on the adjustable jaw extending along the serrated member, a pawl pivotally mounted on the arm, and formed with a lip on one side of its fulcrum, and a wedge point on the opposite side, a slotted arm carried by the pawl engaging the shank, and serrated member, and resilient means on the arm designed to force the wedge pointed pawl in engagement with the serrations.

2. The adjustable wrench claimed in claim 1, in which the extending arm is formed with a pair of shoulders in which the pawl is fulcrumed.

3. An adjustable wrench comprising a shank, a jaw formed integral with one end of the shank, an adjustable jaw slidably mounted on the shank, an extension formed integral with the adjustable jaw, a pawl pivotally mounted on the extension, a member slidably mounted on the shank and formed with a serration on its upper face, a slotted arm carried by the pawl designed to engage the shank and the serrated member, and means on the extension to keep the pawl in engagement with the serrations.

In witness whereof I have hereunto set my hand in the presence of two witnesses.

WILLIAM ALEXANDER MARTIN.
